UNITED STATES PATENT OFFICE.

GEORGE I. KING, OF MIDDLETOWN, PENNSYLVANIA.

UNDERFRAMING FOR RAILWAY-CARS.

SPECIFICATION forming part of Letters Patent No. 752,685, dated February 23, 1904.

Application filed December 26, 1902. Serial No. 136,703. (No model.)

To all whom it may concern:

Be it known that I, GEORGE I. KING, a citizen of the United States, residing at Middletown, Dauphin county, Pennsylvania, have 5 invented a certain new and useful Improvement in Underframing for Railway-Cars, of which the following is a full, clear, and exact description, such as will enable others skilled in the art to which it appertains to make and 10 use the same, reference being had to the accompanying drawings, forming part of this specification, in which—

Figure 1 is a broken plan view of the underframing of one end of a car embodying my 15 invention. Fig. 2 is a longitudinal sectional view thereof on the line 2 2. Fig. 3 is a transverse sectional view on the line 3 3. Fig. 4 is a plan view of one end of a modified form 20 of underframing. Fig. 5 is a longitudinal sectional view on the line 5 5. Fig. 6 is a transverse section of Fig. 4 on the line 6 6. Fig. 7 is a similar view of the opposite end of 25 a modified form of bolster or transom applicable to my general construction, and Fig. 8 is a detached view of another modification.

The invention relates to new and useful improvements in underframing for railway-cars; and it consists in certain features of construction and arrangement of the parts thereof, all 30 as hereinafter more fully described, and specifically pointed out in the claims.

The object of the invention is to produce a car-underframe of simple and strong construction made up of pressed or structural shapes, 35 the whole being riveted together or secured by any suitable and convenient means.

In the drawings, A indicates the center sills of ordinary formation—such as channels, I-beams, &c.—having, preferably, top and bottom flanges B, as shown.

C indicates the side sills, which are shown as channels and may have their flanges disposed either inwardly or outwardly, as may be desired.

D indicates the floor-beams supported by the center sills and side sills, being secured thereto by means of angles 1, bolted to the webs of the said floor-beams and to the webs of the center sills at the inner ends of said floor-beams and to the webs of said beams and the

webs of the side sills at their opposite ends, the said floor-beams being relatively of less depth than either center sill or side sill, where side sills are used, and located below the upper plane of the same sufficiently far to permit 55 the usual wooden nailing-strips (not shown) to be bolted thereon where a wooden floor is to be used or flush therewith when metallic plates are to be used as a flooring. The body-bolster or transom used with my improved underframing is of the type built in with such underframing and forms a part thereof, as shown in the drawings, wherein the center sills A form the middle portion, above which and extending from side sill to side sill is a 60 cover-plate E, forming one member of such bolster, while the compression member F thereof is connected to the side sills at its ends. The tension member E extends down under the side sills, while brace-bars G, connected 65 at one end to said compression member and at their opposite ends preferably to the flanges of the center sills, complete the structure of the body-bolster or transom, secured to the under side of which is the usual center bearing H. 70

Between the cover-plate E and the top of the center sills A is a plate 2, which is connected by rivets to said sills and cover-plate, while angles K extend from the outer corners 80 thereof to the corner-plates L, which are secured to the side sills C and the end sills C', whereby said plate 2 is materially reinforced, and the corners of the cars are also reinforced 85 against endwise pressure thereat.

Referring to Figs. 1 and 2, it will be noticed that the truss-rods M instead of passing over the body-bolster or transom and engaging with means beyond the same as ordinarily arranged are in this invention connected directly, by means of rivets, to the plate 2, said rivets passing through a flattened portion 3 of said truss-rods and through said plate 2, said plate being bent downwardly, as at 3^a, where said rods are attached thereto, said rods extending 90 from thence downwardly under the queen-posts N in the usual manner.

In the modification shown in Figs. 4 and 5 the plate therein (indicated by 2^a) extends from the cover-plate to a point near the end sill, 100

where it is riveted to the center sills and also riveted thereto throughout the length of said plate, while brackets 4 are riveted to the under side of said plate 2^a and have pintle-bearings in their free end portions, in which are held the pins 5, engaging the eye ends 6 of the truss-rods M', therein shown.

To adapt the outer portions of the transom to various types of side sills and to cars in which "side" sills, so called, are dispensed with, wherein the side sheets serve the same purpose, various types thereof are shown in Figs. 3, 6, 7, and 8, and it will be understood that my invention is not limited in its application to cars having the conventional forms of side sills however constructed.

I am aware that minor changes in the construction, arrangement, and combination of the several parts of my underframing may be made and substituted for those herein shown and described without in the least departing from the nature and principle of my invention.

Having thus described my invention, what I claim as new, and desire to secure by Letters Patent, is—

1. In a railway-car, center sills, transoms, a truss-rod, and supporting means, extending across the center sills and over the transoms, with which are connected the ends of said truss-rod; substantially as described.

2. In a railway-car, center sills, transoms, a truss-rod, and supporting means for the ends thereof extending across the center sills and over and beyond said transoms; substantially as described.

3. In a railway-car, center sills, end sills, a truss-rod, supporting means for said truss-rods supported above the center sills, and connecting means between said supporting means and said end sills; substantially as described.

4. In a railway-car, center sills, truss-rods, transoms, and connections between said truss-rods and transoms supported by the center sill; substantially as described.

5. In a railway-car, center sills, truss-rods, transoms, and pivoted connections between said truss-rods and transoms supported by the center sill; substantially as described.

50 6. In a railway-car, center sills, a transom cover-plate extending laterally across said sills, truss-rod-supporting means connected therewith, and truss-rods extending substantially from transom to transom; substantially as described.

7. In a railway-car, center sills, a transom cover-plate, truss-rod-supporting means connected therewith, and truss-rods connected to said supporting means on the side thereof adjacent to the transverse axis of the car; substantially as described.

8. In a railway-car, center sills, a transom cover-plate, truss-rod-supporting means connected therewith, and truss-rods, the ends of which are connected to said supporting means

on the side thereof adjacent to the transverse axis of the car; substantially as described.

9. In a railway-car, center sills, end sills, a transom, a cover-plate, truss-rods connected therewith, and braces for said plate connected with the end sills and side sills; substantially as described.

10. In a railway-car, center sills, transoms and longitudinal truss-rods, and a plate connected with said transoms for supporting the ends of said truss-rods; substantially as described.

11. In a railway-car, an underframing comprising a transom, and a continuous plate cooperating therewith for supporting longitudinal truss-rods, in combination with such truss-rods; substantially as described.

12. In a railway-car, an underframing including transoms, and truss-rods supported at their ends from means extending laterally across the center sills; substantially as described.

13. In a railway-car, center sills, supporting means above the same intermediate the ends thereof, and supporting truss-rods whose ends are connected with said supporting means; substantially as described.

14. In a railway-car, center sills, supporting means above the same intermediate the ends thereof, and truss-rods whose ends are flexibly connected with said supporting means; substantially as described.

15. In a railway-car, center sills, end sills, and truss-rod supports above the center sills connected directly thereto; substantially as described.

16. In a railway-car, center sills, transoms connected to said center sills, truss-rods, truss-rod supports connected with said transoms and extending laterally above said center sills; substantially as described.

17. In a railway-car, the combination with a truss form of transom including a top cover-plate, of a truss-rod extending longitudinally the car, flexible supporting means for the ends of said truss-rod, which means are connected to the transom cover-plates, and rigid supporting means for the intermediate portions thereof, which rigid supporting means are connected to the center sills and side sills; substantially as described.

18. In a railway-car, center sills, a truss-rod, flexible supporting means for the ends thereof approximately in the plane of the upper portion of said center sills, and rigid retaining means for the intermediate portions below the line of said center sills; substantially as described.

19. In a railway-car, center sills, end sills, a truss-rod, supporting means for the ends thereof connected above said center sills, retaining means for the intermediate portions below the plane of the center sills, and connecting means between said supporting means and said end sills; substantially as described.

20. In a railway-car, center sills, side sills, end sills, transoms extending at each side of said center sills, floor-beams extending from center sills to side sills, queen-posts supporting said floor-beams, longitudinal truss-rods, supporting means for the ends thereof connected with said transoms, and means for connection of said supporting means with the end sills and side-sills; substantially as described. 5
21. In a railway-car, center sills, a transom cover-plate extending laterally across said sills, truss-rod-supporting means connected therewith, floor-beams extending from said center sills laterally, queen - posts supporting said 15 floor-beams, and truss-rods extending substantially from transom to transom; substantially as described. 50
22. In a railway-car, center sills, a transom, a cover-plate therefor, truss-rod-supporting means connected therewith, floor-beams extending laterally from said center sills, queen-posts thereon, and truss-rods connected therewith and to said supporting means on the side thereof adjacent to the axis of the car; substantially as described. 55
23. In a railway-car, center sills, end sills, side sills, floor-beams between said center sills and side sills, queen - posts supporting said floor-beams, and truss-rods at each side of said 30 center sills whose ends are supported by means connected above the center sills; substantially as described. 60
24. In a railway-car, an underframing including transoms, lateral floor - beams and 35 queen-posts supporting said floor-beams, center sills, a cover-plate thereon, and truss-rods supported at their ends from said cover-plate and intermediate their ends supporting said queen-posts; substantially as described. 65
25. In a railway-car, a truss form of transom, center sills passing through said transom and forming struts therefor, a cover-plate connected to said transom, a truss-rod, flexible supporting means for the ends thereof approximately in the plane of the upper portion 45 of said center sills, said supporting means being connected to said transom cover-plate and rigid retaining means for the intermediate portions below the line of said center sills; substantially as described. 50
26. In a railway-car, center sills, a transom cover-plate extending laterally across said sills, truss-rod-supporting means connected therewith, floor-beams extending from said center sills laterally, queen - posts supporting said 55 floor-beams, and truss-rods extending substantially from transom to transom; substantially as described. 55
27. In a railway-car, center sills, a cover-plate, truss-rod-supporting means connected therewith, floor - beams extending laterally from said center sills, queen-posts thereon, and truss-rods connected therewith and to said supporting means on the side thereof adjacent to the transverse axis of the car; substantially as described. 65
28. In a railway-car, center sills, end sills, side sills, floor-beams between said center sills and side sills, queen - posts supporting said floor-beams, and truss-rods at each side of said 70 center sills whose ends are supported by means extending across the center sills; substantially as described. 70
